(57) **CLAIM**

The ornamental design for a crutch, as shown and described.

DESCRIPTION

FIG. 1 is a perspective view of a crutch in accordance with my new design.

FIG. 2 is a rear view of the crutch shown in FIG. 1.

FIG. 3 is a front view of the crutch shown in FIG. 1.

FIG. 4 is a left-side view of the crutch shown in FIG. 1, the right-side view being a mirror image thereof.

FIG. 5 is a top view of the crutch shown in FIG. 1; and,

FIG. 6 is a bottom view of the crutch shown in FIG. 1.
